COMBINATION LOCK

Maurice Etienne Julliard, Paris, France

Application March 6, 1946, Serial No. 652,308
In France November 23, 1943Section 1, Public Law 690, August 8, 1946
Patent expires November 23, 1963

8 Claims. (Cl. 70—387)

1

In French Patent Ser. No. 830,327 a combination lock is described (especially applicable as a door-lock for vehicles) which is operated by means of a key carrying a plurality of pins which are individually adjustable as to their heights and which, when introduced into bores or guide sleeves in the lock, will cause slots or notches provided at the ends of tumblers slidably received in said guide-sleeves to come into alignment, such alignment first allowing the swivelling of a fence to actuate the lock bolt.

The present invention has for its object improvements in locks of this type for the purpose of extending its application to pieces of furniture, doors, etc.

According to a first feature of the invention the slots or notches are provided at the peripheries of combination cams of discs which are actuated by the tumblers through the medium either of links or racks or gear wheels.

The slots or notches are variously located at the peripheries of the several combination discs and in such manner that the slots or notches in the various discs will be brought into alignment with one another by unequal displacements of the related tumblers, the height of the projecting portion of each pin being proportional to the travel of the corresponding tumbler.

In one particular embodiment a swingable fence is adapted to engage the slots or notches in the combination discs after the same have been brought into alignment, said fence subsequently causing a latch to rock clear of the lock bolt.

The lock in the unlatched condition can be rotated to the extent of a definite angle for the actuation of the bolt either by means of a fork or preferably by means of gear wheels, in which case the teeth are brought into engagement upon a slight axial displacement of the lock as a unit.

In a modified embodiment the lock unlatching means may consist of a fixed fence whereby a definite inward movement of the lock is only possible when the alignment of the slots in the combination discs is obtained, said inward movement resulting in the engagement of the teeth for the actuation of the bolt (spur wheel and ring, or rack-and-pinion, or equivalent arrangement).

The members (links or racks depending on the design) which provide for the connection between the tumblers and the combination discs can be made to act upon members angularly adjustable with respect to said discs instead of directly actuating the latter or gear wheels rigid therewith,

2

which makes it possible to alter the combination of each disc.

In one particular embodiment, the connecting links are pivoted to a hub on which each combination disc has a tight fit.

In another embodiment, the rack rigid with each tumbler meshes with a pinion carrying a spider whose spring arms are pressed against the combination disc to which movement is imparted by the engagement of projections on said arms into depressions or notches in the disc.

The casing in which the barrel, the tumblers and the combination discs are housed and which can be moved inwardly to set the bolt-actuating teeth into engagement can be latched in either its protracted or its retracted position with the aid of a latch projecting through either hole of a pair drilled in the casing, so that the lock can be made inoperable even by somebody possessing the right key, while the latching in the protracted position allows the combination to be altered at will by adapting the position of the notches in the discs to the adjustable effective height of the pins on the key.

25 The back drum of the lock which provides the bolt-actuating pinion can be operated from the inside by means of a knob.

The lock is provided at the outer side thereof with a keeper plate having a pair of notches cut 30 therein which, in combination with a pair of shoulders on the key body, provide a bayonet coupling by which the key is retained once it has been engaged, which relieves the user from the necessity of maintaining his pressure for the operation of the lock.

Further details of the invention will be more specifically pointed out in the following description taken in connection with the appended drawing in which several embodiments of this 40 invention are illustrated, for merely indicative purpose, as follows:

Figure 1 shows a fundamental form of the lock and the key therefor, the lock being shown in sectional view taken on line I—I in Fig. 3;

45 Figure 2 is a side sectional view taken on line II—II in Fig. 1;

Figure 3 is a rear view showing a specific bolt-actuating means;

50 Figure 4 is a fundamental view of a modification of the lock in which the fence is stationary and the lock can be moved inwardly as a whole;

Figure 5 is a perspective view of an improved embodiment proceeding from the one just mentioned;

Figure 6 is a detail view showing the connection of the links;

Figure 7 illustrates another modification in sectional view taken on line VII—VII in Fig. 8;

Figure 8 is a sectional view taken on line VIII—VIII in Fig. 7;

Figure 9 illustrates an angularly adjustable connection between the tumblers and the combination discs;

Figure 10 illustrates the lock with removed cap and bolt;

Figure 11 shows the bolt-actuating drum.

The key 1 carries in known manner pins 2 whose effective heights can be adjusted by means of screws 3 having knurled heads 5 which may be manipulated in slots which are cut in key 1 and in which said heads are received, a catch-like action thus being obtained by the pressure of springs 6.

On the other hand, set in a rotatably mounted lock plate 9 are guiding sleeves 8 in which tumblers 7 are slidably received which are urged by springs 13 and are adapted to actuate combination discs 10 which are provided with notches 14 at various locations of their peripheries.

The tumblers 7 may be connected with said discs 10 by means of racks 11 integral with said tumblers and co-operating with pinions 12 fixed to discs 10 (Figs. 1 and 2).

Such connection could also be attained by links 61 (Figs. 4 to 6) pivoted both to tumblers 7 and to discs 10, or by any other suitable connecting means.

It will be appreciated that by shifting the tumblers 7 a suitable distance with the aid of pins 2 whose effective heights are accordingly adjusted, it is possible to bring the gates or notches 14 into alignment.

In the example shown in Figs. 1 to 3 a U-shaped fence 15, mounted for swinging motion about the axis 16 carried in a frame 10 operatively connected with plate 9, is enabled, once said alignment is obtained, to engage into the notches 14 in response to the action of a spring 17. In the course of such movement the fence, through the medium of a dog 18, becomes operative upon a latch 19, biased by a spring 20 and swingable about axis 16, to disengage said latch from the slot in bolt 21 in which it has been engaged hitherto, which releases the bolt 21 that henceforth can be actuated by any suitable means, e. g. (Fig. 3) by the rotation of plate 9 which will shift said bolt 21 through the medium of a fork 24 (which limits the stroke of the bolt) or of the spur wheel 62 and the spur ring 63 as in the case of the example shown in Fig. 4, or of a pinion 35 and a rack 36 similarly to the arrangement provided in the examples shown in Figs. 5 and seq.

A push button 22 operable from the outside and acting upon a leg 23 (Fig. 1) of latch 19 allows disengagement of the fence 15 from the notches 14 and to latch the lock again, e. g. when going out, without using the key (since the springs 13 will bring back the plungers 7 to their released positions and throw the notches 14 out of alignment).

In the modification shown quite diagrammatically in Fig. 4 the fence 15 is stationary while the aggregate consisting of plate 9, the guiding sleeves 8, the tumblers 7 and the discs 10 (with which they are connected by rod links 61), which as a whole is enclosed in a casing or a simple housing 42, can be shifted longitudinally to the extent of some millimeters and protracted in the

direction shown by the arrow F provided the notches 14 are aligned and will thus allow the fence 15 to engage therewith. Such shifting will bring the pinion 62 into engagement with the spur ring 63 (or the rack 36 as in the example shown in Fig. 5) so that the bolt can be actuated. A spring 46 will retract the whole structure to its starting position.

In the improved embodiment shown in Figs. 5 and 6, which is based upon the above principle, the connecting links 61 are pivoted at one end thereof to a hub 64 (Fig. 6), instead of directly to the (twin-jaw) discs, which are tightly fitted on said hub, the latter allowing adjustment at will of the discs 10 angularly for the purpose of changing the combination. All the hubs 64 are threaded on one and the same shaft 26 rotatably mounted at the ends thereof in casing 42.

The fence 15 which is fixed in the direction of movement of the tumblers 7 is carried by the rear rotatable drum 32 which forms a pinion 35 designed to engage with the teeth 36 of a rack formed on the bolt 21.

The casing 42 itself, which is centrally guided in drum 32, has notches 23 and can be shifted for a few millimeters while the notches 14 in the discs are engaged by fence 15.

Interposed between drum 32 and a collar 47 on shiftable casing 42 is a return coil spring 46 which permanently tends to shift the casing and the parts carried by it clear of fence 15, as shown by the arrow F'. Said casing can be arrested in either position by means of a latch 67 which will be held by collar 47, said latch being operable from the outside of said casing by appropriate means such as lever 67'.

By making the casing 42 (for instance during night time) immovable in its retracted position (clear of the fence 15), the block becomes inoperable even by somebody possessing the right key, while following the latching of casing 42 in its position of engagement on the fence (as shown in Fig. 5) it will be possible, with the locked discs, to change the "combination" by angularly adjusting the hub 64 with respect to the discs 10, by altering the effective heights of the pins 2 of the key. If necessary for the purpose of the said adjustment, the tumblers 7 can be outwardly pushed by means of a smaller spindle threaded into a hole 7' tapped in each tumbler 7. During such an adjustment the discs 10 will skid on their respective hubs.

The drum 32 acting as pinion 35 can at all times be operated from the inside with the aid of a knob 40.

Finally, a plate keeper 44 formed with a pair of slots 51 will preferably be secured in front of the lock to retain the key 1 once the same has been inserted for unlocking purposes, said key being formed with shoulders 52 in the fashion of a bayonet coupling. The key thus will not be pushed back (direction F') by the action of spring 46 if the user should fail to go on pushing the key in the direction F.

In the improved embodiment shown in Figs. 7 to 11 a barrel 9 is provided in which tumblers 7 are returned to their positions of rest by springs 13 accommodated in the hollows of the tumblers 7 which are formed at their sides with racks 11 (Fig. 9) projecting through a slot 30 and cut lengthwise of a generatrix of guiding sleeves 8 into a recess 31 (Fig. 8) provided in the barrel 9.

Each pinion is coupled with a corresponding disc 10 (freely mounted on the common shaft 26)

by a spider 25 (Fig. 9) carried by the pinion and whose spring arms are pressed against the disc 10, small projections 28 at one end of said arms projecting into depressions 27 in the disc (Fig. 8), whereby the discs 10 (and the notches 14 therein) can be adjusted angularly as desired.

By suitably rotating the discs 10 the notches 14 therein are brought into alignment with one another and with a groove 29 (Fig. 8) provided in barrel 9, which groove is engageable by a tongue 34 for the actuation of bolt 21.

An additional groove 29' and an additional tongue 34' are provided (Fig. 8) in order to improve the connection.

Drum 32 is rotatably mounted in the housing 38 of the lock and the handle or the knob necessary for the operation of the lock from within a room is secured on a central projection 39 of said drum.

The bolt 21 and the barrel 9 are housed in the lock casing 41. As regards this barrel, the same is rigidly connected by a screw 43 (Fig. 7) with the casing 42 which in turn is arranged in a housing 44 provided at the front side thereof with an aperture 45 for the accommodation of the key, said aperture being slotted at 51 as already pointed out.

This lock operates similarly to the one last-described (Figs. 5 and 8).

The barrel 9 with its casing 42 can be shifted in the direction of the arrow F (Fig. 8) as a result of sufficient thrust being exerted thereon with the key inserted through the aperture 45 in housing 44 to overcome the resistance of spring 46. However, such a protraction of the barrel is only possible when the grooves 29, 29' therein register with the tongues 34, 34' on drum 32 and when the notches 14 in discs 10 all register with groove 29.

By this shifting motion the barrel 9 is rigidly coupled with the back drum 32 and any rotation of the barrel will result in a rotation of the back drum 32 and through it of pinion 35 for actuating the bolt 21.

The key can only be inserted through the aperture 45 in the housing 44 in the diametrical plane through the slots 51, which plane corresponds to the plane of alignment of tumblers 7. From the very beginning of the rotation the shoulders 52 on the key engage behind the circular wall of the housing 44, whereby the key 1 is retained from being ejected by the thrust of spring 46. The user is thus enabled to operate the key without being compelled to exert any further pressure.

As soon as the key, after a revolution, is again in registry with the slots 51 the key is ejected from the opening 45.

The lock bolt 21 can be actuated at any time with the aid of a knob 40 or a handle or another equivalent member without the barrel 9 being operated, provided that no key pins are inserted in the lock.

With a key inserted in the lock the latter can be operated just as easily, except that the key 1 will be pushed out as soon as it comes into alignment with the tumblers 7.

In order to bring about registry between the tongues 34, 34' on the back drum and the grooves 29, 29' in the barrel, the back drum 32 is provided at its periphery with a pair of notches 53 (Fig. 11) into which a catch 54 (Fig. 10) can enter which is carried by a spring strip 55 secured to the lock casing 41. The two positions of tongues 34, 34' which are angularly spaced by 180° from each other, are thus marked by the catch 54 acting as a stop.

If the bolt 21 is to serve both as a dead bolt and a spring bolt, a spring 56 must then be arranged in the casing 41 to act upon the bevel-headed bolt.

A stop 57 can be secured in the case for limiting the travel of the spring when the bolt becomes a dead bolt.

The lock thus described affords complete safety in operation and is wholly pick-proof although its adjustment is an extremely simple one.

A lock designed as described above can be used just as well in houses as on automobiles or trunks or for other purposes. It can also be applied wherever movable parts are to be locked.

It will be readily appreciated that this invention admits of manifold embodiments and that alterations can be made in details of the above-described arrangement without thereby departing from the spirit of this invention.

I claim:

1. In a combination lock operable by means of a key carrying a plurality of pins of different lengths; a lock casing, a bolt guided in said casing for movement in two opposite directions, a frame rotatably mounted in said casing about an axis at right angles to the direction of movement of said bolt and provided with a plurality of bores in which said key pins are adapted to be inserted, a spring actuated tumbler in each of said bores and adapted to be moved against the action of said spring towards the interior of the casing when said key pins are introduced into said bores, locking discs corresponding to the number of tumblers and rotatably mounted in said frame, each disc being provided with a notch, means connecting each of said tumblers with a corresponding disc whereby said discs may be rotated to bring the notches thereof in alignment with one another upon movement of said tumblers by said key pins into said bores, a fence rotatable about said axis at right angles to the direction of movement of the bolt and adapted to be engaged in said notches when the same have been brought into alignment position upon introduction of said pins into said bores, whereby said frame, tumblers, locking discs and fence form then a rotatable unit, and cooperating means on said fence and on said bolt and adapted to move said bolt when said unit is rotated by said key.
2. In a combination lock operable by means of a key carrying a plurality of pins of different lengths; a lock casing, a bolt guided in said casing for movement in two opposite directions, a frame rotatably mounted in said casing about an axis at right angles to the direction of movement of said bolt and provided with a plurality of bores in which said key pins are adapted to be inserted, said frame being slidably guided in said casing in the direction of its axis of rotation, spring means adapted to urge said frame towards the exterior of said casing, a spring pressed tumbler in each of said bores and adapted to be moved towards the interior of the casing when said key pins are introduced into said bores, parallelly disposed locking discs rotatably mounted in said frame, each disc being provided with a notch on its periphery, means connecting each of said tumblers with a corresponding disc and adapted to rotate said discs and to bring said notches of all the discs in alignment when said tumblers are moved by the key pins upon introduction thereof into said bores, a fence rotatably mounted about said axis at right angles to the direction of the movement of the bolt and adapted to be engaged in said notches when the

7 same have been brought into alignment upon introduction of said pins into said bores and when said frame has been moved in the direction of said axis of rotation against the action of said spring means, whereby said frame, tumblers, locking discs and fence form then a rotatable assembly, and means operatively connected with said fence and with said bolt and adapted to cooperate when said frame has been moved inwards so as to move said bolt when said assembly is rotated by said key.

3. A combination lock according to claim 2, in which said frame is provided with at least one recess adapted to engage said fence when said frame is moved inwards.

4. A combination lock according to claim 2, including an operating member provided on the exterior of the casing and on the side opposite to that of said bores and operatively connected with said fence in order to move the bolt independently of said frame.

5. A combination lock according to claim 2, including a latch member operable from the exterior of said casing and adapted to cooperate with said frame in order to maintain said frame 25 in any one of its two extreme positions in the direction of said axis of rotation.

6. A combination lock according to claim 2, in which said casing is provided at a slight distance from the bores in said frame with a wall having a circular aperture concentric with said axis of rotation, and two diametrically opposite notches 30

5 for the passage of the key provided in the inner periphery of said aperture.

7. A combination lock according to claim 1, in which said means connecting a tumbler with a disc comprises a hub on which said disc is adapted to be frictionally engaged in different angular positions, and a connecting rod pivoted at one end to said tumbler and at the other end to said hub.

8. A combination lock according to claim 1, in which said means connecting a tumbler with a disc comprises a shaft on which said disc is freely rotatable, a pinion secured on said shaft, means between said pinion and said disc adapted to connect said pinion and disc in different angular relative positions, and a rack operatively connected with said tumbler and meshing with said pinion.
